UNITED STATES PATENT OFFICE.

DANIEL F. FAULK, OF HOLT, FLORIDA, ASSIGNOR OF ONE-HALF TO WILLIAM C. GRIFFITH, OF HOLT, FLORIDA.

VALVE-COUPING.

1,190,136.

Specification of Letters Patent.

Patented July 4, 1916.

Application filed August 27, 1914. Serial No. 858,886.

To all whom it may concern:

Be it known that I, DANIEL F. FAULK, a citizen of the United States, residing at Holt, in the county of Santa Rosa and State 5 of Florida, have invented certain new and useful Improvements in Valve-Couplings; and I do hereby declare the following to be a full, clear, and exact description of the invention, such as will enable others skilled in 10 the art to which it appertains to make and use the same.

This invention relates to new and useful improvements in valve couplings, and has for its principal object to provide a link by 15 means of which the valve mechanism of a horizontal steam engine may be reversed.

Another object of the invention is to provide a device which is capable of being secured to any type of steam engine and 20 which will effectively operate thereon.

A further object of the invention is to provide a device which will be easily and quickly adjusted without inconveniencing the operator.

25 With these and other objects in view, the invention consists in the novel combination and arrangement of parts which will be fully set forth in the following specification and accompanying drawings, in which,

30 Figure 1 is a diagrammatic view of the valve controlling mechanism showing the same in its neutral position, Fig. 2 is a view similar to Fig. 1 showing the device in its reversed position, Fig. 3 is an enlarged detail elevational view of the reversing device, a portion thereof being in section to more 35 clearly illustrate the details of construction, Fig. 4 is an edge view of Fig. 3, Fig. 5 is a top plan view of Fig. 3, Fig. 6 is a sectional view taken on line 6—6 of Fig. 3, and Fig. 7 is an enlarged detail sectional view of the 40 connecting bolt.

Referring now to the drawings by characters of reference, the numeral 1 designates 45 the cylinder of an ordinary steam engine which is provided with the usual steam-chest 2. The usual piston rod 3 is slidable in the cylinder and is connected in the ordinary manner to the fly-wheel 4. This fly- 50 wheel is rigidly carried by the shaft 5 upon which the eccentric 6 is secured. This eccentric 6 is provided with the usual eccentric strap 7 carrying the eccentric rod 8, the free end of which is connected to the link, as 55 will be more fully hereinafter described.

The usual valve rod 9 is slidable in the steam chest 2 and is connected at its free terminal to the cross-head 10, which is slidable between the guide bars 11. This cross-head 10 is provided with a suitable connection by 60 means of which the links may be secured.

The link, which is designated generally by the numeral 12, comprises the S-shaped body 13 having extending longitudinally therethrough the S-shaped slot 14. This body 65 13 is provided with a suitable handle 15 which extends laterally from the center thereof in direct alinement with the extension 16 which is slotted as at 17, and provided with the vertical apertures 18 and 19 70 which are arranged to receive the bolt 20 and wedge 21 respectively. This member 16 is arranged to form the connection for the eccentric rod 8 hereinbefore referred to.

Slidable in the slot 14 of the link 12 are 75 the blocks 22 and 23 carrying the flanges 24. These flanges 24 are arranged to overlie a portion of the body 13 and one of the flanges carries a suitable set screw 25 which is arranged to extend through a threaded 80 aperture formed therein and project into suitable recesses 26 which are formed in the body 13 at spaced intervals. These blocks 22 and 23 are held in operative relation by means of the bolts 27 arranged to pass 85 through bolt receiving openings as illustrated in the drawings. Formed centrally of the blocks 22 and 23 is the transversely extending aperture 28 which is arranged to receive the sleeve 29 having the longitudinal 90 bore 30 through which the bolt 31, forming the connection for the cross head, extends. This bolt 31 is provided with a suitable longitudinal bore which communicates at its inner end with a transverse bore which 95 extends through the periphery of the bolt, and it will thus be seen that oil may be placed in the bolt and will flow to the periphery thereof, thereby providing for means whereby the same is lubricated to 100 prevent undue wear on the periphery of the bolt and interior bore of the sleeve 29.

It will be apparent from the foregoing that in use the link is placed in position on the cross-head 10 of the valve rod and connected thereto as hereinbefore described. The eccentric rod 8 is then connected to the eccentric 6 as illustrated in Fig. 3 and when the engine is set in motion it will be evident that the parts will operate in their normal 110

position. Should it be desired to reverse the engine the handle 15 is grasped and the thumb screw 25 released to permit the link to be slid upwardly with relation to the blocks 22 and 23 and the cross-head 10 in either an upward or downward position, which will change the position of the eccentric rod 8 with relation to the valve and thereby reverse the engine. In raising or lowering the link, the direction in which the same is operated is determined by the direction in which the engine travels, and it will thus be seen that a simple and efficient reversing device which may be attached to any type of horizontal engine, is provided.

While in the foregoing there has been shown and described the preferred embodiment of this invention, it is to be understood that such changes may be made in the combination and arrangement of parts as will fall within the spirit and scope of the invention as defined in the appended claims.

Having thus described my invention, I claim:

1. A valve link comprising a substantially S-shaped body having a longitudinal slot extending approximately the whole length thereof, a pair of parallel arms formed centrally on and extending laterally from the side of said body intermediate the ends thereof, a handle formed on the opposite side and extending laterally from the center thereof in direct alinement with the arm, said arms provided with vertical apertures, blocks slidably mounted in the slot in the body of the link, flanges formed on opposite faces of the slots of the blocks and engaging the sides of the body, one of said flanges provided with a set screw, said body provided on its outer face with a plurality of spaced screw-threaded apertures adapted to receive the set screw therein for holding said blocks in any desired position within said body, said blocks provided centrally with transversely extending openings, a sleeve arranged in said opening, a bolt extending through said sleeve, said bolt connecting said blocks to the cross head, substantially as set forth. 45

2. A valve link comprising a substantially S-shaped body having a longitudinal slot extending approximately the full length therethrough, a pair of parallel arms on one side of the body centrally thereof, a handle on the opposite side of said body and in direct alinement with the arms, valve blocks slidably mounted in said slots, flanges on opposite faces of said blocks engaging the outer faces of the body, one face of said body provided with a plurality of spaced screw-threaded openings, a set screw extending through one of the flanges of the block, and engaging any of the openings on the body for holding the blocks at any desired adjustable position with the slot of the body, means extending through said block for securing the same to the cross head, said blocks also provided with a central opening, a sleeve in said opening, a bolt arranged in said sleeve, and means extending through the arms for forming adjustable connection for the eccentric rod whereby wear may be taken up substantially as set forth. 50

2. A valve link comprising a substantially S-shaped body having a longitudinal slot extending approximately the full length therethrough, a pair of parallel arms on one side of the body centrally thereof, a handle on the opposite side of said body and in direct alinement with the arms, valve blocks slidably mounted in said slots, flanges on opposite faces of said blocks engaging the outer faces of the body, one face of said body provided with a plurality of spaced screw-threaded openings, a set screw extending through one of the flanges of the block, and engaging any of the openings on the body for holding the blocks at any desired adjustable position with the slot of the body, means extending through said block for securing the same to the cross head, said blocks also provided with a central opening, a sleeve in said opening, a bolt arranged in said sleeve, and means extending through the arms for forming adjustable connection for the eccentric rod whereby wear may be taken up substantially as set forth. 55

In testimony whereof I affix my signature in presence of two witnesses.

DANIEL F. FAULK.
